(57) **CLAIM**

The ornamental design for a mold detection system, as shown and described.

DESCRIPTION

FIG. 1 is a perspective view of the mold detection system with the cover in the fully closed position;

FIG. 2 is a front view of the mold detection system with the cover in the fully closed position;

FIG. 3 is a right side view of the mold detection system with the cover in the fully closed position;

FIG. 4 is a left side view of the mold detection system with the cover in the fully closed position;

FIG. 5 is a top view of the mold detection system with the cover in the fully closed position;

FIG. 6 is a bottom view of the mold detection system with the cover in the fully closed position;

FIG. 7 is a rear view of the mold detection system with the cover in the fully closed position;

FIG. 8 is a bottom view of the mold detection system with the cover in the fully opened position;

FIG. 9 is a perspective view of the mold detection system with the cover in the fully opened position;

FIG. 10 is a front view of the mold detection system with the cover in the fully opened position;

FIG. 11 is a rear view of the mold detection system with the cover in the fully opened position;

FIG. 12 is a right side view of the mold detection system with the cover in the fully opened position;

FIG. 13 is a left side view of the mold detection system with the cover in the fully opened position; and,

FIG. 14 is a top view of the mold detection system with the cover in the fully opened position.
